WILLIAM M. SHEEHAN, OF ST. LOUIS, MISSOURI, ASSIGNOR TO GENERAL STEEL CASTINGS CORPORATION, OF GRANITE CITY, ILLINOIS, A CORPORATION OF DELAWARE

OIL-ELECTRIC-LOCOMOTIVE PLATFORM

Application filed November 14, 1929. Serial No. 407,145.

My invention relates to railway vehicles and consists in a platform structure arranged to support an engine and a generator.

Economy of weight is of particular importance in the construction of a railway car which carries its own source of power and power unit. This type of car was devised to meet the demands of local transportation where the same is not great enough to support regular train service. A car of this type is apt to be called upon to compete with bus service and consequently, the economy of the bus construction and operation must be considered in constructing the car.

Weight should be restricted to make it possible to use a small economical motor and thus save in first cost and in the cost of operation.

Since the size of the car is limited, the power unit should take up as small a space as possible in order to leave the maximum portion of the car for the accommodation of passengers. As a small power unit means a limitation of the power, there is again the necessity of economizing in the matter of weight in the car construction.

With a view to lightening the structure of this type of car, I have devised an integral structure consisting of a platform and engine and generator base by which I eliminate a substantial amount of weight which would be required if the platform structure were structurally complete in itself and the engine and generator base applied thereto in the usual manner.

The main object of my invention is to provide an integral platform and power plant supporting structure that will mount the power plant above the level of the floor of the vehicle, and I produce a structure of less weight than an assembled structure of the same strength would have, and I save the expense of a great deal of the machining, drilling and fitting incident to an assembled structure. Also the embodiment in a unitary structure permits greater strength and rigidity, thus greatly reducing the ill effects of vibratory forces and eliminating maintenance.

This general and other more detailed objects of my invention are attained by the

structure illustrated in the accompanying drawings in which—

Figure 1 is a top view of my platform and supporting structure.

Figure 2 is a side elevation of my platform and supporting structure, showing the motor and generator mounted thereon.

Figure 3 is in part a cross section and in part an end view of my platform and supporting structure taken substantially on the line 3—3 of Figure 1.

Figure 4 is a transverse vertical section of my platform and supporting structure taken substantially on the line 4—4 of Figure 1.

The platform includes an end sill 1, longitudinal sills 2 and a bolster 3. The longitudinal sills are connected by additional cross members 4 and together function as spaced longitudinal pulling and buffing members.

The longitudinal sills 2 have deepened portions 8 at their forward ends beneath and adjacent to the end sill and these deepened portions are spaced rather close together to accommodate a coupler draw bar and draft rigging (not shown) which will be mounted between the lugs 9. The sills 2 diverge rearwardly of portions 8 and upstanding webs 5 thereon are provided with top flanges 6 having finished pads 6a to which the engine crank case E may be bolted. Webs 5 are reinforced with suitable ribs 7 and between ribs 7 are provided with openings 10 whereby the structure is lightened without material sacrifice of strength.

At the rear of the bolster 3, sills 2 are offset inwardly as shown at 11 for attachment to the car center sills 11a. The webs 5, however, extend upwardly from the brackets 12a on bolster 3. These brackets and webs are offset outwardly as shown at 12 to accommodate an electric generator G of greater width than the engine E, the flanges 6 continuing to the rear of the structure for mounting the generator.

Suitable horizontal flanges 15 extend throughout the structure and at the level of the tops of the end sill and bolster serve to mount the floor plates F and the ends of the end sill and bolster have depressed flanges 100

13 adapted to mount the lower sills S of the car side wall structure.

The structure is illustrated as comprising a one piece casting and such is the preferred construction of my platform, but it is within the spirit of my invention to form some of the parts separately and unite them by welding into an integral whole having the advantages of a single casting.

10 The construction described provides for efficient distribution of metal in a platform adequate to carry the weight of the power plant and superstructure and to transmit the buffing and pulling forces without undue increase in weight over an ordinary platform. 15 The lower portion of the crank case of the engine may be removed and access to the interior of the crank case is unobstructed. The casting of the platform makes possible the use of suitable gusset-like elements 14 for strengthening the structure without clumsy overlapping joints requiring surplus material and difficult to get at. The platform is always rigid as there are no bolted or riveted 20 connections to loosen up. Hence the alignment of the power plant parts is maintained and the operation of the engine and generator improved. Obviously the general objects of my invention as stated in the introductory part of this specification are attained to a marked degree.

I have illustrated and described a single embodiment of my invention and it will be understood that the details of the structure 35 may be varied without departing from the spirit of my invention. I contemplate the exclusive use of all the modifications of my structure which come within the scope of my claims.

40 I claim:

1. In a railway car underframe, a pair of longitudinal sills including floor supports, said sills being spaced apart at their forward ends to form a draft gear mounting and 45 more widely spaced apart at the rear of said mounting, upward extensions on the more widely spaced portions of said sills providing supports for an engine located above the level of said floor supports, said sills extending rearwardly of said supports and their extensions being more closely spaced together 50 for connection with the car center sills.

2. A car underframe integral structure comprising a bolster, a longitudinal sill, and upstanding members on said sill on either side of said bolster for supporting an engine and generator respectively.

3. A car underframe integral structure comprising a bolster, a longitudinal sill, upstanding members on said sill on either side of said bolster for supporting an engine and generator respectively, and an integral connection between said members spaced above said sill.

4. In a railway vehicle end platform cast-

ing, an end sill, an adjacent bolster, and supports between and integral with said sill and bolster for cradling an engine.

5. In a railway vehicle platform having longitudinal sills, a bolster, spaced longitudinal members integral with said sills and bolster and extending upwardly therefrom, said longitudinal members being arranged to support an engine and a generator and being spaced a greater distance apart at the rear 75 of said bolster at their generator supporting portion than in front of said bolster at their engine supporting portion.

6. In a railway car underframe, a pair of longitudinal sills including floor supports, 80 upstanding structures on portions of said sills providing supports for an engine located above the level of said floor supports, said sills converging forwardly of said engine supports to form a draft gear mounting. 85

7. In a railway car underframe end platform, a pair of longitudinal sills including floor supports, said sills being spaced apart at their forward ends to form a draft gear mounting and more widely spaced apart at 90 the rear of said mounting, upstanding structures on the more widely spaced portions of said sills providing supports for an engine located above the level of said floor supports, said structures extending in diverging directions at the rear of the platform and forming more widely spaced supports for a 95 generator.

8. In a railway car underframe platform, a pair of longitudinal sills including floor supports, said sills being spaced apart at their forward ends to form a draft gear mounting and more widely spaced apart at the rear of 100 said mounting, upstanding structures on the more widely spaced portions of said sills providing supports for an engine located above the level of said floor supports, the rear portions of said sills extending rearwardly of said supports and said portions being closer together for connection with the 105 car center sills, said upstanding structures diverging at the rear of the platform and forming more widely spaced supports for a 110 generator.

9. A car underframe integral platform 115 comprising a bolster, a longitudinal sill extending from one side of said bolster, a bracket extending from the other side of said bolster, upstanding members on said sill and bracket on both sides of said bolster, and a longitudinal member supported by said upstanding members and forming with them supporting structures for an engine on one side of said bolster and a generator on the other side of said bolster and forming a bridge between said supporting structures over said bolster.

10. A car underframe integral platform comprising a bolster, a longitudinal sill extending from one side of said bolster, a

bracket extending from the other side of said bolster, and engine supporting and generator supporting structures respectively upstanding on said sill on one side of said bolster and from said bracket on the other side of said bolster.

11. A car underframe integral platform comprising a bolster, a longitudinal sill extending from one side of said bolster, a bracket extending from the other side of said bolster, and engine and generator supporting structures respectively upstanding on said sill on one side of said bolster and from said bracket on the other side of said bolster, said bracket and generator supporting structure being spaced farther from the longitudinal center of the platform than said sill and engine supporting structure.

12. In a railway vehicle end platform structure, upstanding power plant support elements integral with at least a portion of said structure and integral rearwardly projecting elements adapted to be secured to the adjacent underframe.

13. As a new article of manufacture, an integral structure comprising a railway vehicle end platform member having upstanding power plant support elements thereon, said member being adapted to be secured to adjacent portions of the vehicle underframe.

In testimony whereof I hereunto affix my signature this 8th day of November, 1929.

WILLIAM M. SHEEHAN.
